(57) **CLAIM**

The ornamental design for a watch dial as shown and described.

DESCRIPTION

FIG. 1 is a front view of a watch dial showing a first state in a sequence showing our new design; FIG. 2 is a front view showing a second state thereof; FIG. 3 is a front view showing a third state thereof; FIG. 4 is a front view showing a fourth state thereof; FIG. 5 is a front view showing a fifth state thereof; FIG. 6 is a front view showing a sixth state thereof; FIG. 7 is a front view showing a seventh state thereof; and, FIG. 8 is a front view showing an eighth state thereof. The broken lines depict portions of the watch dial and form no part of the claimed design. The claimed design sequentially transitions between FIGS. 1 and 8, i.e., from the first state to the eighth state in the sequence.
